UNITED STATES PATENT OFFICE.

ALBERT H. THIELE, OF NEW YORK, N. Y., ASSIGNOR TO GEO. BORGFELDT & CO., OF NEW YORK, N. Y., A CORPORATION OF NEW JERSEY.

DESIGN FOR A BED-PAN.

43,834.

Specification for Design.

Patented Apr. 8, 1913.

Application filed January 7, 1913. Serial No. 740,730. Term of patent 14 years.

To all whom it may concern:

Be it known that I, ALBERT H. THIELE, a citizen of the United States, and a resident of the city of New York, county of Kings, and State of New York, have invented a new and original and ornamental Design for Bed-Pans, of which the following is the specification, reference being had to the accompanying drawing, forming part thereof, in which—

Figure 1 is a plan view of the bed pan and Fig. 2 is a side elevation thereof.

I claim:

The ornamental design for a bed pan, as shown.

Signed at the city, county and State of New York, this 3rd day of January, 1913.

ALBERT H. THIELE.

Witnesses:

GUSTAVE I. ARONOW,
H. RADZINSKY.
